SAFETY SYSTEM RESPONSIVE TO TEMPERATURE AND FLUID FLOW

Robert A. Wittmann, Chicago, Ill., assignor to
Chicago By-Products Corporation, a corpora-
tion of Illinois

Application May 26, 1938, Serial No. 210,144

4 Claims. (Cl. 200—81)

5 My invention relates, generally, to safety systems for gas burners of the type disclosed in my Patent No. 2,185,490, and it has particular relation to systems of this nature in which controls are provided that are responsive to both temperature and fluid flow.

10 In devices for the automatic fuel control to heating apparatus employing a fan or blower to force or draw air over the heating sections or heat transfer surface, it is desirable and often necessary to be assured that the air is passing over the heating surfaces before the main burner is put into operation. At the same time it is also necessary to be assured that fuel cannot be fed 15 to the main burner unless the pilot flame or other ignition means is either burning or in satisfactory operative condition.

20 An important object of my invention is to provide for checking as to whether or not the pilot is burning at each time that there is a demand or call for heat.

25 Another important object of my invention is to prevent the main burner of a heating system from going into operation unless air is passing over the heating or heat transfer sections to which heat is applied from the flame of the main burner.

30 A further object of my invention is to provide a simple form of safety pilot system employing principally a strip of metal and thereby eliminating the usual moving parts that are complicated by linkages and leverages, electric contacts, bleed valves, and other sources of likely causes of trouble.

35 Still another object of my invention is to provide a safety pilot control system which, when the pilot burner is lighted, will go into operation in a predetermined time, preferably in about thirty seconds, so as to give the operator ample 40 time to move away from the furnace before the main burner is lighted and which will shut down or cause to shut down the main burner quickly in case that the pilot burner is extinguished. Samples of my control system capable of effect- 45 ing the foregoing objects have been operated successfully and consistently for shutting down the main burner within approximately three seconds after the extinguishment of the pilot burner, even with the main burner on.

50 A further object of my invention is to provide a safety pilot system which does not require any adjustments, thereby eliminating tampering by unauthorized or inexperienced persons.

55 Other objects of my invention will, in part, be obvious and in part appear hereinafter.

Accordingly, my invention is disclosed in the embodiment thereof shown in the accompanying drawing and it comprises the features of construction, combination of parts, and arrangement of elements which will be exemplified in the construction hereinafter set forth and the scope of the application of which will be indicated in the appended claims.

For a more complete understanding of the nature and scope of my invention reference may 10 be had to the following detailed description taken in conjunction with the accompanying drawing in which the single figure illustrates a concrete embodiment of my invention.

Referring now particularly to the drawing, it 15 will be observed that the reference character 10 designates, generally, a gas heated hot air furnace. The furnace 10 may be a conventional coal fired hot air furnace with its grates removed and a main gas burner 11 installed, as is the 20 practice in changing from burning coal to gas.

A fan 12 is located in the cold air return 13 for drawing in cold air and forcing it over the heating surface 14 of the furnace 10 and out through the hot air pipes 15. The fan 12 is 25 driven by a suitable motor 16 which may be connected by means of conductors 17 and 18 to the energized conductors 19 and 20. For example, the conductors 19 and 20 may be connected to a source of 110 volt alternating current. A 30 switch 21 is provided in conductor 18 for controlling the operation of the motor 16 as desired.

The main gas burner 11 in the fire box of furnace 10, may be connected by a pipe 25 to a gas supply main 26 through a shut-off valve shown, 35 generally, at 27. The shut-off valve 27 comprises a valve port 28 which may be closed by a valve body 29 that is operated by an electromagnet 30. For purposes of illustration the valve body 29 is shown as being lifted off of the valve port 28. 40 It will be understood, however, that when the electromagnet 30 is deenergized, the valve body 29 will drop and close the valve port 28, thereby preventing the flow of gas through the shut-off valve 27.

45 With a view to lighting the main gas burner 11 a pilot burner 31 is provided that is connected by a suitable pipe 32 to the supply main 26. It will be understood that, under normal operating conditions, the pilot burner 31 is lighted continually.

The electromagnet 30 may be energized from the energized conductors 19 and 20. One terminal of electromagnet 30 is directly connected to the energized conductor 20 through a conduc- 55

5 conductor 33. The other terminal is indirectly connected to the energized conductor 19 through a conductor 34, containing in series a mercury control switch 35, and conductor 18 through switch 21. Thus the electromagnet 30 can not be energized until both the mercury control switch 35 and switch 21 are closed.

10 The conductor 11, connecting one terminal of the motor 16 to the energized conductor 20, contains in series a thermostatic switch 40. This thermostatic switch 40 may be any one of several different types and might be located in a position to be responsive to the temperature of a room heated by the furnace 10. When the room gets 15 to a predetermined temperature the contact at 41 will open and the motor 16 driving the fan 12 will be turned off. It is also seen that when the room cools sufficiently the contact at 41 will be closed and the fan 12 started, thereby again 20 forcing air through the furnace 10 to heat the room.

25 When the fan 12 is stopped and not forcing air over the heating surface 14 the main burner 11 should be turned off for two reasons. First, if air is not passing over the heating surface 14 when the main burner 11 is heating it, it may become overheated and may be seriously damaged by the high temperature to which it will be raised. Secondly, when the fan 12 is not running, the 30 rooms heated by furnace 10 are warm enough and the heat from the main burner 11 is not needed.

35 With a view to causing the main burner 11 to be put in operation only when the fan 12 is running, a control mechanism shown, generally, at 42 is provided. The control mechanism 42 operates the mercury control switch 35 which has been shown to be connected in series relationship with electromagnet 30. This mercury control switch 35 may be of the type having a pool of 40 mercury 43 which is moved from one end to the other of the switch in accordance with tilting thereof. The control switch 35 is mounted for operation on a suitable operating member or shaft 44.

45 The control mechanism 42, besides controlling the operation of the main gas burner 11, also performs the safety measure of not allowing the shut-off valve 27 to open unless the pilot 31 is burning. It is seen that this is very important, 50 as it would be extremely dangerous to have gas escaping unignited through the main burner 11.

55 In order to operate the switch 35 in accordance with whether or not the pilot 31 is burning, an arm 45 is provided extending downwardly from shaft 44 and having at its lower end a permanent magnet 46, having a horseshoe shape. Cooperating with the permanent magnet 46 is a member 47 of Curie point metal, in the shape of an angle. The vertical leg of member 47 is arranged to bridge 60 between the ends of the permanent magnet 46 and the horizontal leg is positioned in thermally conductive relation to the flame of the pilot burner 28. When this flame is absent, the temperature of the member 47 is below the Curie point and 65 possesses magnetic properties. When the pilot burner 31 is lighted and the member 47 is heated above its Curie point, it loses its magnetic properties to such an extent that it functions as if it were made of non-magnetic material.

70 When the pilot burner 31 is not lighted, the member 47 of Curie point metal possesses magnetic properties. Since the member 47 is stationarily mounted, the permanent magnet 46 is attracted and held in contact with the member 47 75 and, since the permanent magnet 46 is mechani-

cally connected to the shaft 44 carrying the switch 35, the latter is held in the position illustrated in the drawing, which is the open circuit position. As long as the pilot burner 31 remains unlighted, the permanent magnet 46 will hold itself in engagement with the member 47 of Curie point metal and thereby will hold the switch 35, controlling the electromagnet 30, in the open position. When the pilot burner 31 is lighted, the member 47 of Curie point metal will be heated and will 10 lose its magnetic properties and the permanent magnet 46 will no longer cling to it. However, the rotating force due to the weight of the permanent magnet 46 is so counterbalanced by the adjustable weight 48, that when the member 15 47 is heated and therefore the permanent magnet 46 is not attracted to it, the shaft 44 will rotate slightly so that permanent magnet 46 no longer engages member 47. It will, however, not rotate sufficiently to tilt the switch 35 enough to close 20 it. This may be called the intermediate position of the permanent magnet 46. As the result, switch 35 will still remain in the open position until some outside force is applied to the shaft 44 for rotating it sufficiently to close it. 25

This outside force is supplied by the draft from the fan 12. For this purpose the shaft 44 has extending upwardly therefrom an arm 49 which carries at its upper end a sail member 50. As illustrated, the sail member 50 is positioned 30 in the path of the air from fan 12. This blast of air from the fan 12 is sufficient to cause the sail member 50 to move and rotate the shaft 44 for operating the control switch 35 to the closed position, provided that the pilot burner 31 is 35 lighted and the permanent magnet 46 is not attracted to the member 47 of Curie point metal.

With a view to describing the operation of my safety system responsive to temperature and fluid flow, assume that the pilot burner 31 is lighted, 40 the main burner 11 is out, and that the fan 12 is stopped. Under these conditions the permanent magnet 46 will not be attracted to the member 47 and under the effect of gravity it will move to the intermediate position not touching the member 47. As there is no draft of air from the fan 12 the control switch 35 will be in the open position, thereby, causing the electromagnet 30 to be deenergized. Now if the room in which the thermostatic switch 40 is positioned cools sufficiently, the contact at 41 will be closed on the 45 action of the thermostatic switch 40 and the fan 12 will be started. When the fan 12 starts the sail member 50 will be acted on by the draft set up and thereby cause the control switch 35 to close. When the control switch 35 closes the electromagnet 30 will become energized and gas will flow to the main gas burner 11 and will be lighted by the pilot burner 31. After the room is heated sufficiently, the thermostatic switch 40 50 will open the contact at 41 and cause the fan 12 to stop. When the fan 12 stops there will no longer be a draft against the sail member 50 and consequently the control switch 35 will open, 55 thereby deenergizing the electromagnet 30 and shutting off the gas supply to the main gas burner 11. 60

It will be seen, from the description of the operation given above, that if the pilot burner 31 should go out for some reason and the fan 12 65 should be started by the closing of the contact at 41, the switch 35 would not be closed as the permanent magnet 46 would cling to the member 47 and as a result no gas would flow to the main burner 11. But, since the air forced through fur- 70 75 80 85 90 95

nace 10 by the fan 12 is not heated the thermostatic switch 40 will not open the contact at 41 and the fan 12 will continue running indefinitely. In order to prevent an occurrence of this nature, a bell or other alarm 55 may be connected to the conductor 17 by the conductor 56 as shown. The other terminal is connected to conductor 18 by the conductor 57 through the switch 58. As shown, one contact member of the switch 58 is carried on a projection of the downwardly projecting member 45. The switch 58 is so set up that it will not be closed unless the permanent magnet 46 is clinging to the member 47 of Curie point metal as shown in the drawing. Now, it will be seen that if the pilot burner 31 should go out the switch 58 will close and the bell 55 will give warning of the condition.

It is to be understood that the alarm 55 and the corresponding contacts 58 may optionally be omitted. In that event, the movable system including magnet 46 need not shift to the intermediate position heretofore described. That is to say, when the Curie point material 47 loses its magnetic properties the magnet 46 need not move away, even though no attraction between the parts 46 and 47 exists. When this attraction ceases, the draft acting on the sail 50 is free to shift the movable system to the desired position of closing the switch 35 or performing any other desired operation. Thus, when the alarm 55 is not incorporated, the permanent magnet 46 may engage the member 47 at all times except when it is forced away by a draft acting against the sail member 50.

Since certain further changes may be made in the foregoing construction and different embodiments of the invention made without departing from the scope thereof, it is intended that all matter shown in the accompanying drawing or described hereinbefore shall be interpreted as illustrative and not in a limiting sense.

I claim as my invention:

1. Safety control means responsive to temperature and fluid flow comprising, in combination, a control switch, magnetic means operatively connected to said control switch, a body of Curie point material, and sail means operatively connected to said control switch, said magnetic means being attracted to said body of Curie point material

when said body is below its Curie point, there being substantially no attraction between said magnetic means and said body of Curie point material when said body is at a temperature above its Curie point.

2. Control means responsive to temperature and fluid flow comprising, in combination, a control switch, relatively movable cooperating magnetic means and Curie point metal means, one of said means being operatively connected to said control switch for controlling its operation according to whether the temperature of said Curie point metal means is above or below its Curie point, and fluid flow responsive means also operatively connected to said control switch and adapted to control its operation in accordance with change in fluid flow.

3. Control means responsive to temperature and fluid flow comprising, in combination, a rockable member, switch means operated from one position to another by said rockable member, relatively movable cooperating magnetic means and Curie point metal means, one of said means being operatively connected to said rockable member for moving it from one position to another according to whether the temperature of said Curie point metal means is above or below its Curie point, and fluid flow responsive means also operatively connected to said rockable member for moving it from one position to another in accordance with change in fluid flow, said switch means being operable from one position to another only under predetermined conditions of both temperature and fluid flow.

4. Control means responsive to temperature and fluid flow comprising, in combination, switch means carried on a rockable shaft, a permanent magnet carried by said shaft, a body of Curie point metal in cooperative relation to said magnet for controlling the position of said shaft according to whether the temperature of said Curie point metal is above or below its Curie point, and a sail carried by said shaft for controlling its position in accordance with change in fluid flow, said switch means being operable from one position to another only under predetermined conditions of both temperature and fluid flow.

ROBERT A. WITTMANN.
